UNITED STATES PATENT OFFICE.

JAMES A. PIETSCH, OF ST. GEORGE, NEW YORK.

DESIGN FOR A DOOR.

Application filed May 29, 1928. Serial No. 26,900 Term of patent 14 years.

To all whom it may concern.

Be it known that I, JAMES A. PIETSCH, a citizen of the United States, and a resident of St. George, Staten Island, in the county of Richmond and State of New York, have invented the new, original, and ornamental Design for Door, of which the following is a specification.

Reference is had to the accompanying drawing, forming part thereof, wherein

I claim:

The ornamental design for a door substantially as shown.

Signed at New Brighton, in the county of Richmond and State of N. Y., this 24 day of May, A. D. 1928.

JAMES A. PIETSCH.
